UNITED STATES PATENT OFFICE

149,598

DESIGN FOR A LUGGAGE HANDLE

Alexander C. Weiss, Chicago, Ill.

Application November 27, 1946, Serial No. 135,133

Term of patent 7 years

(Cl. D87—2)

To all whom it may concern:

Be it known that I, Alexander C. Weiss, a citizen of the United States, residing at Chicago, in the county of Cook and State of Illinois, have invented a new, original, and ornamental Design for Luggage Handle, of which the following is a specification, reference being had to the accompanying drawing, forming part thereof.

Fig. 1 is a perspective view of the luggage handle, showing my new design.

Fig. 2 is a side view.

Fig. 3 is a top plan view.

I claim:

The ornamental design for a luggage handle, as shown.

ALEXANDER C. WEISS.
